ABSTRACT OF THE DISCLOSURE

A method of segmenting a continuous ribbon of sharpened razor strip stock. Pairs of tabs are placed on the strip adjacent each other. A first tab and corresponding portion of strip material are held and the adjacent tab and corresponding portion of strip material are moved transversely to the first portion to break the strip material.

This invention relates to a method for segmenting strip material and more particularly to a method for forming strip segments from a continuous ribbon of thin steel having a razor edge thereon for use in strip razors of the type disclosed in U.S. Patent No. 3,262,198.

A number of criteria must be met in any operation for segmenting a continuous ribbon of sharpened razor steel. Manufacturing tolerances require that segmenting be accomplished with a high degree of accuracy and with a clean, even break. At the same time, it is desirable that segmenting tools be avoided which have sharpened cutting edges which will dull through wear and which will require frequent and expensive replacement. Obviously, any segmenting operation for material having a razor edge must also avoid creating risk of any damage to the delicate edge.

It is therefore a principal object of this invention to provide a segmenting method for simply and accurately segmenting a continuous ribbon of razor steel with minimal risk of damage to the razor edge thereof. It is also an object of this invention to provide a segmenting method which will reconcile the apparently conflicting criteria of accuracy and avoidance of cutting edges.

It has been discovered that the objects of this invention may be achieved in a method in which pairs of tabs are placed on the strip adjacent each other and in which the strip is segmented by transverse movement of one of the tabs relative to the other thus breaking the strip between the tabs. The tabs stiffen the strip thereat to permit breaking without cutting. Additionally, they provide readily detectable and adjustable reference to assure accuracy in segment sizing.

In general, this invention, a method in which the strip material is held, a one portion, and an adjacent portion of the strip material, is moved transversely relative thereto for segmenting the material. In the preferred embodiment of the invention, a pair of reinforcing tabs are positioned adjacent each other in abutting relation, each tab defining one of the said portions.

Other objects, features, and advantages of this invention will be appreciated by those skilled in the art from the following detailed description thereof in conjunction

2

with the description of particular apparatus for performing the method together with the accompanying drawings in which:

FIG. 1 is a diagrammatic plan view of segmenting apparatus according to the invention;

FIG. 2 is an enlarged elevation of a portion of the strip material having tabs placed thereon prior to segmenting;

FIG. 3 is an enlarged side elevation of the supply station of the apparatus taken along the lines 3—3 of FIG. 1;

FIG. 4 is a view taken along the lines 4—4 of FIG. 3;

FIG. 5 is a view similar to FIG. 4 showing a different operating position of the tension control and brake assembly at the supply station;

FIG. 6 is an enlarged plan view of fine adjustment and tab detector mechanism utilized in the apparatus;

FIG. 7 is a view along the lines 7—7 of FIGS. 1 and 6, enlarged from the view of FIG. 1;

FIG. 8 is a reduced diagrammatic view similar to FIG. 6 showing a different operating position of the fine adjustment and tab detector mechanism;

FIG. 9 is an enlarged plan view of bidirectional tension control mechanism utilized in the apparatus;

FIG. 10 is an enlarged isometric view of the segmenting station of the apparatus;

FIG. 11 is an enlarged end view of the trailing pair of segmenting jaws;

FIGS. 12 and 13 are views similar to FIG. 11 showing different operating positions of the trailing jaws;

FIG. 14 is an enlarged isometric view of the lead pair of segmenting jaws;

FIGS. 15, 16 and 17 are diagrammatic plan views of the segmenting jaws in different operating positions thereof;

FIG. 18 is a partially exploded isometric view from below of the segmenting jaws;

FIG. 19 is a fragmentary view taken along the lines 19—19 of FIG. 10; and

FIG. 20 is an enlarged view taken along the lines 20—20 of FIG. 19.

As will be seen from FIG. 1 of the drawings, the segmenting apparatus 10 includes a plurality of components linearly arranged (the bends in the strip 14 path shown in FIG. 1 being used only to diagrammatically indicate continuity thereof) between a supply station 30 and the segmenting station 120. Pullout rollers 49 positioned in

the strip path after supply station 30 draws the strip 14 from the coil 13 thereof at supply station 30. Pullout rollers 49 draw the strip 14 from coil 13 at the average speed of the strip through the remainder of apparatus 10. As shown in FIG. 2 the strip 14, of razor steel, has a razor edge 15 which is fed in an upright position through apparatus 10 to avoid damage thereto.

A tension control and brake assembly 33 is provided between pullout rollers 49 and supply station 30 for exerting a tensional force on strip 14 at the coil 13 thereof at station 30 in the direction of rotation thereof and for braking the coil in response to a tension decrease below a predetermined level.

After pullout rollers 49 the strip 14 path forms a slack loop containing a greater amount of strip material therein than a segment length thereof, which loop is maintained by a flow of air from jet 50. Photoelectric cell detectors 52 are provided at the position of the loop to sense any increase in the loop beyond the position therebetween to

signal pullout rollers 49 to slow down or stop. Microswitch 53 detects and signals any loss of the loop. From rollers 49 movement of strip 14 through apparatus 10 is incremental, the slack loop, however, permitting the strip 14 to be drawn from coil 13 at a relatively constant speed.

From the loop the strip 14 proceeds between guide rollers 54 and thence to a vacuum tension control block 56 which exerts a retarding force on the strip 14 as it passes therefrom. The vacuum tension control block 56 simply comprises a block adjacent the side of the strip path having perforations at that side through which a vacuum is applied to the side of the strip 14. The frictional engagement of the strip 14 and the block 56 thereby engendered creates a tension in the strip 14 from that point forward in the apparatus.

From the vacuum tension control block 56, the strip 14 passes through a series of inspection stations 20 which are adapted to detect any defects in the strip 14 and to store the information in a mechanical memory cell (not shown) to signal actuation of a rejects mechanism at a later stage when the strip 14 reaches the rejects mechanism. Details of structure and function of these inspection stations may be had with reference to copending patent application, assigned to the same assignee as this application Ser. No. 586,843, filed Oct. 14, 1966, entitled "Strip Inspection System."

From the inspection stations the strip path extends through tab placement apparatus 58 which is positioned three strip segment lengths from the segmenting means 122, later to be described, for operation in the stopped position of the incremental movement of strip 14 therethrough. At the tab placement apparatus 58 tabs 16 and 17, FIG. 2, comprising generally U-shaped members with a perforation 18, 19 on one side thereof are fed from feed bowls 60 and placed on strip 14 side by side. The tabs are fastened at placement apparatus 58 to the strip 14 by punches which move through apertures 18 and deform the strip material and portion of tabs 16, 17 therewith. Also at apparatus 58 is another vacuum tension control block 57, similar to block 56, to assist in tensioning the strip 14 and to prevent wavering of the strip 14 as tabs 16, 17 are placed thereon.

In the embodiment disclosed in FIG. 2, the apertures 18, 19 are placed as far as possible from the abutting ends of the tabs 16, 17 to provide extra strength; however, depending on the materials used, it may be possible to position the apertures in the center of the tabs so that there will be no need to distinguish between right and left hand tabs. The tabs 16, 17 are of electrically conductive material for testing at the next station in the apparatus 10.

From the tab placement apparatus the strip path moves through fine adjustment and tab detector apparatus 62 which adjusts the position of the strip 14 prior to the placement of the next set of tabs 16, 17 by placement apparatus 58 to assure accuracy of placement thereof, and which detects the presence or absence of tabs and in the absence of one or more tabs signals an apparatus stop circuit.

From the fine adjustment and tab detector mechanism 62 the strip 14 moves to bidirectional control apparatus 98 which prevents any slack from moving backwardly through the strip 14 thereby to maintain tension therewith and which also functions to exert a retarding tensioning influence on the strip 14 as it passes therefrom to the segmenting station 120 next in the line of the strip path.

Finally, the apparatus 10 is provided with a segmenting station 120 at which means are provided for pulling the strip through the apparatus, for segmenting the strip at the position between tabs 16, 17, for depositing the strip in trays 174 on a conveyor 176 therebelow, and for rejecting a defective strip segment.

In greater detail, supply station 30 includes a rotatable table 32 mounted on apparatus frame 11 as shown in FIGS. 3 and 4 on which a coil 13 of strip razor steel 14 is mounted with its sharpened edge 15 up, as in FIG. 2.

As in perhaps best shown in FIG. 4 the tension control and brake assembly 33 at station 30 includes a tension arm 34 pivotally mounted coaxially of table 32 about shaft 35. Arm 34 extends generally in the direction of the path of strip 14, as it leaves the coil 13, and has on the end thereof a pair of freely rotatable guide rollers 36 through which the strip 14 passes as it is drawn by pullout rollers 49. A spring 38 is interconnected between an extension 37 on arm 34, to the other side of pivot 35 from guide rollers 36, and a stationary post 39 mounted in frame 11 thereby biasing arm 34 in the direction of rotation of table 32 and creating a tensioning force on a strip 14 between coil 13 and pullout rollers 49.

Brake arm 40 having a brake surface 41 adapted to engage the circumferential surface of table 32 is pivotally mounted by pivot pin 42 on a post 43, mounted in frame 11, for movement against and away from table 32. A spring 44 interconnected between brake arm 40 and another post 45 mounted in frame 11 normally biases the brake arm 40 toward table 32. A link 46 pivotally connected to extension 37 by pivot pin 47 interconnects tension arm 34 and brake arm 40. The link 46 is connected to arm 40 by shaft 48 fixedly mounted on brake arm 40 and slidably positioned within a slot 51 in the end of link 46 thereadjacent, slot 51 extending generally in the direction of movement of link 46.

In operation, if tension in the strip 14 as it leaves coil 13 is reduced the spring 38 exerts a force on arm 34 to move that arm in the direction of rotation of the coil thereby to exert a tension between the coil 13 and pullout rollers 49. As arm 34 thus rotates, spring 44 urges brake arm 40 into engagement with table 32 to apply a braking force thereto. Elongated slot 51 allows arm 34 to continue to rotate, under the influence of spring 38, and take up slack between coil 13 and pullout rollers 49. As tension is increased in the strip 14, the procedure is reversed and the other end of slot 51 engages shaft 48 overriding the biasing force of spring 44 to move the brake arm 40 away from table 32, to permit free rotation thereof.

Springs 38 and 44 are selected for strength, and the moment arms thereof positioned, so that the force exerted by the spring 44 is substantially less than that of spring 38 as otherwise it obviously would be impossible to release the brake.

The fine adjustment and tab detector apparatus 62, shown in FIGS. 6-8, includes a channel 64 through which strip 14 passes. One wall of the channel 64 is defined by a conductive wall 63 spaced from strip 14 by a distance equal to the thickness of the legs of tabs 16, 17 thereadjacent. Opposite wall 63 is a movable electrode carrier block 66 spaced two strip segment lengths from the segmenting means 122. Block 66 carries a pair of electrodes 68, 70. Block 66 is movable toward and away from wall 63 to complete an electric circuit between electrodes 68, 70, conductive tabs 16, 17 and wall 63 to determine the presence or absence of the tabs. The absence of the tab, signalled by an incompletely closed current, is used to signal the apparatus stop circuit.

Fine adjustment of the strip 14 relative to tab placement apparatus 58 is accomplished by tab adjustment arm 72 positioned to the rear of electrode 16 relative to the direction of strip movement thereby. Arm 72 is pivotally mounted at its middle portion on a pivot pin 75. One end 73 of the arm, adapted for engaging the rear edge of the trailing tab 16 of a pair, is positioned adjacent electrode carrier block 66 and the other end 71 thereof is interconnected by spring 78 with a stationary member 80, affixed to apparatus frame 11, to bias end 73 toward the strip 14. Pivot pin 75 connects arm 72 to the end of one leg 79 of an L-shaped member 74. Member 74 is pivotally mounted at pin 76 to frame 11. The leg 79 of member 74 extending between pivots 75, 76 is generally at right angles to arm 72 thereby carrying arm 72 in a direction generally parallel to the path of strip 14 on pivotal movement of the leg 79.

about pivot 76. The other leg 77 of member 74, extending rearwardly from pivot 76, is biased by spring 94, extending therefrom to actuating arm 90, in a direction of counterclockwise rotation, for normally maintaining adjustment arm 72 in a position as shown in FIG. 8 remote from the tab positions at electrodes 68, 70. Spring loaded push rod 92 bears against the other leg 77 of member 74 and on movement of actuating arm 90, best shown in FIG. 7, actuates member 74 and arm 72 for movement of arm 72 to a position adjacent electrode 68. A stationary guide pin 82 engages an inclined surface 84 of arm 72 between pivot 75 and rear end 71 thereof to control the movement of the forward end 73 thereof to and away from the path of strip 14, as shown in FIGS. 6 and 8. Threaded members 86, 88 positioned to engage member 74, for limiting movement thereof in opposite directions, may be adjusted to control the stroke of arm 72 so that the forward end 73 thereof will stop precisely at a position one strip segment length from the rear edge of a tab 16 being placed by placement apparatus 58 therebehind.

In operation as a tab moves into channel 64 and stops during the increment movement of strip 14, arm 90 is actuated to rotate member 74 clockwise thereby to move arm 72 to a tab 16 engaging position, FIGS. 6 and 7. The tab 16 is thereby engaged at its rear edge by lead portion 73 of adjustment arm 72 and is moved, if necessary, to an accurate position relative to tab placement apparatus 58, one segment length therefrom, prior to the placement of a next set of tabs 16, 17. Immediately thereafter the electrode carrier block 66 is advanced to engage the tabs and a current is passed through electrodes 68, 70 to detect their presence or absence and to signal an apparatus stop circuit if one or both of the tabs is missing. The block 66 is in no event, however, advanced further than the maximum distance which would be required to complete a circuit through the electrodes 68, 70, tabs 16, 17 and wall 63. The electrode carrier 66 is then retracted and the actuating arm 90 is released causing retraction of adjustment arm 72 before the strip 14 is again moved.

Bidirectional tension control mechanism 98 shown in FIG. 9 is provided immediately after the tab adjustment and detecting apparatus 62. The tension apparatus 98 includes two pairs of rolls 100, 102, and 104, 106. The nip of lead rolls 104, 106 is positioned slightly less than one strip segment length behind the stopped position of a trailing tab 16 of a pair in the segmenting means 122 so that the lead tab 17 of a pair just engages the rear edges of the nip therebetween as the strip 14 stops during incremental movement thereof. The surfaces of rolls 104, 106 are of resilient material, such as rubber, so that any forward force exerted on the strip 14, other than a force drawing the lead tab 17 into the nip of the rolls 104, 106 will create a slight amount of retarding tension.

One of the trailing rolls 100, 102 moves only in a forward direction at the nip thereof, as by a one-way clutch, to prevent any slack created by the back pressure of rolls 104, 106 on tab 17 from passing behind the tension control mechanism 98 thereby causing loss of tension through apparatus 10 to vacuum tension block 57. One of the trailing rolls also is mounted for transverse movement relative to the path of strip 14 and is biased against the other roll by a spring 101 to create a gripping pressure on strip 14 and to permit passage of tabs 16, 17 thereby. The bidirectional tensional control mechanism 98 is mounted on a bracket 110 via fasteners 108. Slots 109 at the fasteners 108, permit adjustment of the control mechanism 98 for proper positioning of the nip of rollers 104, 106.

The segmenting station 120 is next provided and includes segmenting means 122, blade deposit mechanism 124, traverse mechanism 126, as shown in FIG. 10, and rejects mechanism best shown in FIGS. 19 and 20.

The segmenting means 122 best shown in FIGS. 11-18, includes two pair of segmenting jaws 140, 141 and 142 closely spaced together as shown in FIGS. 15-17. Lead jaws 142 are supported on vertical rotatable shafts 144 which are interconnected by gears 146 for opening and closing jaws 142. One of the lead jaws 142 is provided with an extension arm 143 to which actuating rod 148 is connected tangentially for rotating the jaw about shaft 144. The interconnection of gears 146 causes simultaneous movement of the other of the jaws 142. The bite of the jaws 142 lies in the path of strip 14 and shafts 144 are spaced from the bite of the jaws 142 generally along the path of the strip. The lead jaws 142 each have a recessed configuration providing stops or shoulders 150 in the direction toward which the strip is moving. Each of the shoulders 150 has a depth less than the thickness of one leg of the U-shaped tabs 16, 17 thereby permitting pressure to be exerted by the jaws 142 directly on the tabs rather than on strip 14. As best illustrated in FIGS. 16 and 17 the recessed configuration has a length from shoulders 150 along the path of strip 14 exactly equal to the length of the tab thereon.

Trailing jaws 140, 141, FIG. 11, also have a bite along the path of strip 14. The trailing jaws 140, 141 extend to a common pivot below the bite and are there pivotally supported by pivot pin 154 from bracket 152. The trailing jaws 140, 141 cross in scissors fashion at pivot 154 extending therefrom to ends 151, 153 spaced apart. The ends 151, 153 of jaws 140, 141 are connected to links 160, 162 which in turn are connected to vertically movable actuating rod 166. Links 160, 162 are connected to rod 166 therebelow by pivot pin 164 vertically aligned with pivot pin 154, and one of the links 160 is connected by pivot pin 156 to the end 151 of one of the jaws 140. The other jaw 141 is connected at its end 153 to link 162 by a shaft 158 slidably positioned in a slot 168 of the link 162 outwardly inclined relative to pivot 164. Spring 170 interconnecting shaft 158 and pivot pin 164 biases the end of jaw 141 to the lower end of slot 168, the lower end of the slot 168 being positioned for abutment with shaft 158 in a vertical position of the bite of jaws 140, 141.

Hence on movement of rod 166 upwardly, as in FIG. 13, the jaws 141, 142 open symmetrically about the path of strip 14 as links 160, 162 are forced outwardly bearing upon pin 156 and shaft 158. One movement downwardly of rod 166, however, the jaws first close as in FIG. 11 and then as rod 166 continues to move downwardly the force exerted through link 160 causes rotational movement of both jaws 140, 141 about pivot 154 transversely of the strip path and of lead jaws 142 and shaft 158 approaches the upper end of slot 168 of link 162 as in FIG. 12. This transverse movement causes segmenting of the strip 14 clamped therein between tabs 16, 17.

Preferably the trailing jaws 140, 141 as shown in FIGS. 15-17 do not extend all the way to the rear of trailing tab 16. Also, as shown in FIG. 18, preferably the bite of jaws 140, 141 are spaced forwardly of the pivots and links and are spaced apart a substantial distance providing a gap 172 therebetween behind the bite of the jaws 140, 141. This accommodates of the traverse mechanism next to be described.

The traverse mechanism 126 is best shown in FIG. 10 includes a pair of parallel sprocket chains 130 and three pairs of sprocket wheels 132, 134, 136 about which the chains 130 extend. The traverse chains 130 are driven through sprocket wheel 134 and a clutch (not shown) which slips when the segmenting jaws 140, 141 and 142 engage tabs 16, 17. Carried on the sprocket chains 130 are three traverse jaws 138 normally spring closed. The traverse jaws 138 are spaced apart a distance slightly greater than a strip segment length. Cam surfaces 139 spaced above the trailing segmenting jaws 140, 141 engage 75 the traverse jaws 138 and cause them to open, as they

descend upon a strip 14 at the trailing segmenting jaws 140, 141, and then to close as they are carried to the plane of strip 14 at trailing jaws 140, 141. Pivoted arms (not shown), mechanically operated, open the traverse jaws 138 at the end of the strip segment length. Traverse jaws 138 supply the incremental motive force for the strip 14 after it leaves pullout rollers 49.

The blade deposit mechanism 124 provided at segmenting station 120, shown in FIGS. 10 and 20, includes a vertically movable carrier 182 which is guided along vertical guide posts 184, 186 between the strip path and a position therebelow for depositing strip segments in slots 173 of tray 174 supported on conveyor belt 176.

Slots 173 of tray 174 are provided in vertical walls of the tray which is positioned on a conveyor 176 disposed for transverse incremental movement relative to the path of strip 14 thereabove. At least one wall of tray 174 is resilient to maintain strip segments therein under tension. Holes 175 on the sides of tray 174 are provided at predetermined intervals therealong for indexing the tray in proper position in cooperation with aligning pins (not shown) which are movable to engage the holes 175.

The blade deposit mechanism 124 is provided with gripping jaws 178, 180 aligned with the path of strip 14. Transverse pins 192 extending from jaws 178, 180 within cavities in carrier 182 are adapted to be engaged by inclined surfaces 189, 191 of vertically movable actuating member 190 extending slidably through carrier 182 for opening and closing the jaws. Springs 188 between rearward extensions of jaws 178, 180 and carrier 182 normally bias the jaws to a closed position, however, when the inclined surfaces 189, 191 of actuating members 190 strike pins 192, they override the biasing pressure of springs 188 to open the jaws 178, 180.

The rejects mechanism, FIGS. 19, 20, comprises an inclined rejects trough 194 mounted on a swing bracket 193 and has an air line at the elevated end thereof. The swing bracket 193 is adapted, on a signal from magnetic read out apparatus at stations 20, to move the rejects trough 194 under the path of strip 14 to collect a rejected strip segment. Air supplied through tube 196 thereupon removes the rejected segment to a collection station (not shown).

In operation, at the commencement of a cycle, trailing segmenting jaws 140, 141 are clamped on the lead tab 16 of a strip segment and lead segmenting jaws 142 are opened. Traverse jaws 138 move down over the segmenting means 122 and are opened by cam surfaces 139 and are then closed to engage the strip behind tab 16 as the traverse jaws move into the plane of strip 14. Immediately thereafter, the trailing jaws 140, 141 open and the traverse jaws 138 carry the strip forward, vacuum tension block 56 providing tension to the strip 14 as it is carried forward. As the strip 14 is carried forward, the lead jaws 142 are partially closed, as in FIG. 15, so that the lead tab 17 of a pair will stop against the shoulders 150. As the tab 17 strikes shoulders 150 of lead jaws 142, the clutch through which the traverse jaws are driven slips and movement of the strip ceases. As this occurs both sets of jaws 140, 141 and 142 are clamped tightly on tabs 16, 17, as in FIG. 16. Pullout rollers 49 meanwhile are continuously drawing strip 14 from coil 13 into the loop formed by air jet 50. If excess material is fed to the loop, it is sensed as it interrupts the signal of cells 52. The tension control and brake assembly 33 operates as heretofore described to maintain tension on coil 13.

As the segmenting jaws 140, 141 and 142 are clamped on strip 14 the fine adjustment and tab detecting apparatus 62 is activated for adjustment of the position of tabs 16, 17 thereat if necessary and to detect the presence or absence of the tabs, all as previously described. Immediately after the fine adjustment is made of the tab positions, the tab deposit apparatus 58 places another set of tabs 16, 17 on the strip and the trailing segmenting jaws 140, 141 are activated to move transversely relative to the path of

the strip thereby segmenting the strip 14 between the tabs 16, 17 thereat as shown in FIG. 17. As the segmenting occurs, the fine adjustment and tab detector apparatus 62 is deactivated.

Also, as the segmenting occurs, jaws 178, 180 of the blade deposit mechanism 124 are carried upwardly by carrier 182 to engage the segment extending from the lead jaws 142 to traverse jaws 138. Actuating members 190 are activated and surfaces 189 thereof engage pins 192 to open jaws 178, 180 and then disengage pins 192 to close the jaws 178, 180 on the severed strip segment. The lead jaws 142 are then opened and the blade deposit mechanism moves downwardly carrying the severed strip segment with it to tray 174. As the strip segment is placed in the tray the jaws 178, 180 are again opened by activating actuating members 190 engaging surfaces 191 and pins 192 and the jaws are then moved downwardly to clear the deposited strip segment. Conveyor 176 is then activated to move and index tray 174, in cooperation with the aligning pins (not shown), incrementally, forward to clear jaws 178, 180 which are then closed and moved upwardly again to take the next strip segment.

The timing and sequence of operations is controlled by a number of cams (not shown). In the event the rejects mechanism is activated, the cam pattern is shifted and jaws 178, 180 remain in a position below the strip path at tray 174 during the next cycle and trough 194 is moved under the path of the rejected strip segment. Thereupon, when the rejected segment is released by lead jaws 142 and traverse jaws 138, it falls into the tray and is discarded by air from tube 196.

As the trailing jaws 140, 141 are rotated to segment strip 14, they exert a slight forward movement on strip 14 which normally takes up any slack created by operation of the fine adjustment apparatus 62. The back tension exerted by the nip of the resilient rolls 104, 106 of the bi-directional tensional control mechanism 98 prevents damage to the strip 14, as the traverse jaws 138 descend thereupon after trailing jaws 140, 141 are returned from a transverse position relative to the strip path, by pulling back on the strip 14 to remove any resulting slack between the rolls 104, 106 and trailing jaws 140, 141 thereby maintaining the strip 14 in an erect position. If this provision were not made, the slack created by the transverse and return movement of trailing jaws 140, 141 would result in the traverse jaws 138 striking the sharpened edge 15 of the blade strip 14 thereby damaging the blade. Rolls 100, 102 operate to confine any resulting slack to the bi-directional tension control mechanism 98 between rolls 100, 102 and 104, 106.

Other embodiments of this invention will occur to those skilled in the art which are within the scope of the following claims.

What is claimed is:

1. The method of segmenting strip material comprising the steps of:
placing a pair of reinforcing members of said strip material adjacent each other;
holding a first reinforcing member and corresponding portion of said strip material; and
moving the adjacent reinforcing member and corresponding portion of said strip material transversely relative to said first portion;
thereby breaking said strip material between said adjacent portions.
2. The method claimed in claim 1 in which said members are tabs.
3. The method claimed in claim 1 in which said members are placed on said strip material in abutment with each other.
4. The method claimed in claim 3 in which said members are tabs.
5. The method of segmenting a continuous strip of razor steel having a delicate sharpened razor edge, comprising the steps of:

placing a pair of reinforcing tabs in abutment on said strip;
holding one of said tabs in a stationary position; and moving the other of said tabs transversely relative to said one tab;
thereby breaking said strip between said tabs.

6. The method of separating a continuous strip of razor steel having a delicate sharpened razor edge into a series of razor blade lengths, comprising the steps of:

advancing said strip to a segmenting station,
gripping a first portion of said strip across its entire width at said segmenting station,
gripping a second portion of said strip across its entire width immediately adjacent said first portion at said segmenting station,
moving said gripped second portion transversely relative to said gripped first portion to snap said steel

5

strip between said first and second portions and form a razor blade length,
and repeating said advancing, gripping and transverse moving steps to form additional razor blade lengths from said strip of razor steel.

UNITED STATES PATENT OFFICE
CERTIFICATE OF CORRECTION

Patent No. 3,443,731 Dated May 13, 1969

Inventor(s) Thomas Alan McGill and John George Hoffman, Jr.

It is certified that error appears in the above-identified patent and that said Letters Patent are hereby corrected as shown below:

In the specification at Column 4, line 9, "on" should read --of--. Column 5, line 23, "increment" should read --incremental--. Column 6, line 48, the numeral "16" should read --166--; and at line 68, "wheel" should read --wheels--.

In the claims at Column 8, line 57, "of" (second occurrence) should read --on--.
